UNITED STATES PATENT OFFICE.

CHARLES K. GETCHELL, OF SCHENECTADY, NEW YORK.

COMPOUND LOCOMOTIVE ENGINE.

Application filed April 9, 1926. Serial No. 100,834.

My invention relates to variable operating mechanism for cylinders for compound articulated engines, and particularly to the use of relatively longer cutoffs for the low pressure cylinders than are at present in use. One of the objects of my invention is to provide means for obtaining predetermined variable relations between high and low pressure cutoffs, preferably with a single cutoff lever. My invention also comprises various features which I shall hereinafter describe and claim.

In the accompanying drawings: Figure 1 is a side view, in elevation, of an articulated compound locomotive, embodying my invention, certain of the parts being diagrammatically indicated; Figs. 2 and 3, side and front elevations, respectively, on an enlarged scale, of the reverse lever, and 20 quadrant, diagrammatically indicated in Fig. 1; Fig. 4, a diagram indicating the relation of the high and the low pressure cutoff to the various positions of the reverse lever; Fig. 5, a diagram, indicating the relation of the parts, with a slightly modified form of guide; Fig. 6, a side view, in elevation, of a locomotive embodying a structural modification of my invention; and, Figs. 7 and 8, front and side elevations, respectively, on an enlarged scale, of the auxiliary lever and certain associated parts, used in connection with the modification shown in Fig. 6.

The improvement claimed is hereinafter fully set forth: In the practice of my invention, referring descriptively to the specific embodiment thereof which is herein exemplified in Figs. 1, 2, 3 and 4, the locomotive comprises a boiler 2, high pressure cylinders 3, low pressure cylinders 4, and reverse cylinders 5 and 6 for operating, respectively, the high and the low pressure valve gears. The cylinders 5 and 6 of the power reversing gear are separately controlled by the reverse lever 7 from the cab 8. The operating valve of the cylinder 5 is controlled by the valve operating rod 9, which is connected to the boss 10 on the lever 7, and by the movement of said lever 45 through the reach rod 11 and connections 11^a adjusts the positions of the high pressure valve gear. The operating valve of the cylinder 6 is controlled by the valve operating rod 13, which is connected to the boss 14 on the auxiliary lever 15 and by the movement of the lever through the reach

rod 16 and connections 16^a adjust the position of the low pressure valve gear.

The reverse lever 7 has the usual latch lever 17, link 18 and pawl 19, and is fulcrumed on the pin 20 of the quadrant bracket 21 which supports the quadrant 22. The levers 7 and 15 are pivotally supported on the fulcrum pin 20. The link 23 pivotally connects the auxiliary lever 15 to a 65 crank arm 24 of the bell crank lever, fulcrumed at 25 to the lever 7. The other arm 26 of the bell crank lever carries a pin 27 which operates in a cam slot 28 in the bracket 21. The bosses 10 and 14 are preferably as shown below and above the pin 20.

As the lever 7 is moved from the central position, shown in Figs. 2 and 3, into forward position, the pin 27 on the arm 26 follows the slot 28 in the bracket 21. As the pin 27 moves along the slot 28 its center changes the distance from the pin 20, while the pin 25 as it is mounted on the lever 7 is maintained a constant distance from the pin 20. As the pin 27 moves nearer the pin 20 it necessarily moves the lever arm 26, which in turn through the pin 25 moves the arm 24 with relation to the lever 7. The arm 24 in turn through the link 23 moves the 85 lever 15 so that its center line is advanced to a greater degree than the center of the lever 7. As the valve operating rod 13 connects the boss 14 of the lever 15 with the valve gear for the low pressure cylinders 4, 90 while the rod 9 connects the boss 10 of the lever 7 with the high pressure cylinders 3, this greater movement of the lever 15 results in a longer cutoff in the low pressure cylinders than in the high pressure cylinders for 95 all points of the stroke in forward gear at which the center line of the slot 28 is at a shorter distance from the pin 20 than an arc struck from that point through the original position of the pin 27.

The various positions of the levers are indicated diagrammatically in Fig. 4. Thus the numbers 7—25—20—10 represents the center line of the lever 7 in central position; numbers 20—14—30 the central line of the lever 15 in central position. When the lever 7 has been moved over to the A position, the boss 14 will accordingly be moved over to the 14^a position through the action of the pin 27 acting through the bell crank 110 24—26 and the link 23. When the lever is moved to the end of the stroke to the B po-

sition, the pin 27 reaches the 27^B position in the end of the slot 28, the boss 14 the 14^B position, and the lever 15 is returned to its original relation to the lever 7, with the 5 center line of its lower portion in line with the B position of the lever 7. As the arc of the slot 28 is struck from the pin 20 as a center, it is obvious, as is shown in Fig. 4, that when the lever 7 is moved into re- 10 verse no alteration will take place in the relative positions of the levers 7 and 15.

In Fig. 5 I have indicated diagrammatically a modified form of my improved cutoff mechanism, in which the contour of 15 the left-hand side of the slot 28^a has been changed so that in reverse the pin 27^a in travelling from central position to extreme reverse position indicated at 27^D traverses a path which during most of the move- 20 ment is out of an arc passing through the points 27^a and 27^D and having its center at pin 20^a. When the pin 27^a is moved further away from the pin 20^a than when in its central position it operates through 25 the crank 24^a—26^a and the link 23^a to move the lever 15^a to a point further from the central position than the lever 7^a. It will be seen that center lines of levers 7^a and 15^a coincide between the points 20^a and 14^a in 30 central position, are separated when moved into the A or C position, and are together again in the B or D extreme position.

In the embodiment of my invention shown in Figs. 6, 7 and 8 I have illustrated 35 an articulated compound locomotive having the usual high and low pressure cylinders 33, 34 with the ordinary type of reverse lever 37 and quadrant 52 in the cab 38. The operative order of the reverse cylinder 35 is 40 controlled by the valve operating rod 39, which connects with the boss 40 on the lever 37 and operates through the reach rod 46 and pin connection 47 to move the lever 48 of the variable cutoff mechanism particularly shown in Figs. 7 and 8. The intermediate lever 48 is fulcrumed on the shaft 49, which is supported in the bearings 50 and 51, and has rigidly mounted thereon the auxiliary lever 52. The upper end of the 45 lever 52 is connected by a link 53 to the arm 54 of the bell crank lever, the pivot 55 of which is mounted on the lever 48. The arm 56 of the bell crank carries a pin 57 which operates in a cam slot 58 in the sup- 50 port or bracket 50. The reach rod 61 is connected to a boss 62 on the lever 48 and adjusts the positions of the high pressure valve gear through the reversing linkage 63. The adjustment of position of the low pressure 55 valve gear is operated from the lever 48 through the rod 64, which is connected to an arm 60 of the shaft 49 and passes through the saddle casting of the high pressure cylinders 33 to the reverse shafting and link- 60 ages 65.

It will thus be seen that the embodiment of my invention shown in Figs. 6, 7 and 8 operates on the same principle as that shown in preferred form.

I claim as my invention and desire to 70 secure by Letters Patent:

1. In a compound locomotive, the combination of a reverse gear comprising a high pressure cutoff adjustment lever; a low pressure cutoff adjustment lever; a bell crank 75 lever fulcrumed on one of said levers; and guiding means for one arm of said bell crank lever, the other arm being attached to the other of said reverse levers.

2. In a compound locomotive, the combination of high and low pressure cylinders; a distribution valve for each of said cylinders; a lever operable to adjust the point of cutoff of the valve of the high pressure cylinder; a second lever associated therewith; and means for moving the second lever relatively to the first to vary the length of the cutoff of the valve of the low pressure cylinder with reference to that of the high pressure cylinder. 80

3. The combination, in a locomotive, of a high pressure cylinder; a low pressure cylinder; a distribution valve for each cylinder; and mechanism for automatically varying the degree of cut-off of the valve of one 95 of the cylinders relatively to that of the other, comprising a reverse lever, an auxiliary lever, a bell-crank lever pivotally connected to the reverse lever, a link connecting an arm of the bell crank lever with the 100 auxiliary lever, a cam guide, and means connected to the other arm of the bell crank lever, disposed for traverse along said guide, whereby a differential between the rate of traverse of the reverse lever and the auxiliary lever will be effected. 105

4. The combination, in a locomotive, of a high pressure cylinder; a low pressure cylinder; a distribution valve for each cylinder; and valve controlling mechanism, comprising 110 a power cylinder piston for adjusting the high pressure valve, a power cylinder piston for adjusting the low pressure valve, a manually movable reverse lever for controlling the operation of one of the power cylinder pistons, an auxiliary lever associated with the reverse lever, for controlling the operation of the other power cylinder piston, a bell crank lever, pivoted to the reverse lever, a link connecting one arm of the bell 115 crank lever to the auxiliary lever, a cam guide, and means associated with the other arm of the bell crank lever, disposed for traverse along said guide, whereby a differential between the rate of traverse of the reverse lever and the auxiliary lever, will be effected. 120

5. The combination, in a locomotive, of a high pressure cylinder; a low pressure cylinder; a distribution valve for each cylinder. 130

der; and valve controlling mechanism comprising a power cylinder piston, an intermediate lever, actuated by the piston for adjusting both of the valves, a manually 5 movable reverse lever for controlling the operation of the power cylinder piston, a bell-crank lever pivoted to the intermediate lever, an auxiliary lever, a link connecting

one arm of the bell crank lever to the auxiliary lever, a cam guide, and means, associated with the other arm of the bell crank lever, and disposed for traverse along said guide whereby differential between the rate of traverse of the intermediate lever and the auxiliary lever, will be effected.

CHARLES K. GETCHELL.
